AUTOMATIC CLUTCH CONTROL MEANS FOR
PRESS BRAKES

Harry H. Goldberg, Denver, Colo.

Application December 10, 1951, Serial No. 260,816

2 Claims. (Cl. 192—82)

1

This invention relates to improvements in steel press brakes of the type now extensively employed, and relates more particularly to an attachment for the automatic control of the power transmitting clutch.

Press brakes of the type to which this invention relates have a stationary bed plate, a ram plate positioned thereabove, means comprising a cam shaft having cams operatively connected with the ram plate, means for turning the cam shaft comprising a clutch, and pedal means for controlling the operation of the clutch.

In the operation of presses of this type, the clutch is closed by exerting pressure on a pedal bar and opened when the pressure is removed from the bar. As long as pressure is applied to the bar, the cam shaft continues to turn and the operator must therefore watch the position of the ram plate in order to open the clutch at the proper time. The operator's attention must therefore be divided between the feeding of the press and the control of the clutch to stop the ram plate at the proper place.

It is the object of this invention to provide such presses with means that locks the clutch in operative position when the pedal bar is depressed to close the clutch and which automatically releases the clutch and opens the clutch when the ram plate has returned to a predetermined position at the ends of its cycle.

A further object is to provide an attachment or means that will make it unnecessary for the operator to keep one foot in constant engagement with the pedal bar and limits such engagement to a single application of force at the beginning of each cycle.

The above and other objects of this invention which may appear as the description proceeds are attained by means of a construction and an arrangement of parts which will now be described in detail, for which purpose reference will be had to the accompanying drawing in which

Figure 1 is a perspective view of a well known steel press brake showing the same as it is now marketed, the attachment being indicated in position thereon.

Figure 2 is a side elevation, looking towards the left in Fig. 1, and shows the attachment, which forms the subject of this application, in place thereon;

Figure 3 is a view partly in section and partly in elevation, taken on line 3—3 Fig. 2, showing the attachment to an enlarged scale;

Figure 4 is a side elevation looking towards the left in Fig. 3 and

2

Figure 5 is a view similar to that shown in Fig. 3.

Referring now to the drawing, reference numerals 10R and 10L designate respectively the right and the left sides of the housing. The sides are joined at their tops by a crown section 11. The sides are connected near their lower ends by bars 12 and 13 and bed plate 13a. Cam shaft 14 is mounted for rotation in bearings 15, two of which have been shown. The shaft carries two eccentrics that are surrounded by straps 16 which are adjustably connected with ram plate 17. Power is usually supplied by a constantly operating electric motor, which has not been shown, and motion is transmitted to the cam shaft by a clutch (not shown) which is opened and closed by a pedal mechanism comprising the pivoted levers 18 and rod 18a and pedal rod 19.

The press brake shown in Figs. 1 and 2 is on the market and its construction is well known. The above description has been given merely for the purpose of facilitating the description of the attachment and its operation. Referring now to Figs. 1 and 2, it will be seen that the free ends of levers 18 are connected by a pedal bar or pedal rod. A spring, which is not visible in Fig. 1 serves to hold lever 18 in the elevated clutch open position shown in Fig. 2, and for the purpose of visual clarity a spring S has been shown on the outside and this represents the hidden spring. When the parts are in the position shown in Fig. 2, the clutch is open and the ram plate is stationary. When levers 18 are moved to the position shown by dotted lines in Figs. 2 and 5, the clutch is closed, and shaft 14 turns moving the ram plate in a vertical direction. It is customary to stop the shaft with the eccentrics at top dead center and therefore when the cam shaft begins to turn the ram plate starts moving downwardly. In the usual way of operating the press, the operator must keep his foot on pedal rod 19 until the cam shaft has made a complete turn, which becomes very tiresome.

The invention or attachment to which this application is directed consists of a bracket 21 attached to the ram plate and, a latching mechanism attached to side 10R near its lower end. The latching device consists of a steel casting or forging that has a base 22, which is secured to the side by suitable means such as bolts 23. Extending outwardly from the base is an arm 24 that has two spaced lugs 25 between which is mounted for pivotuation a bell crank shaped member having an arm 26 which extends in a generally horizontal direction and a pawl 27 that extends

vertically. A rod 28 has its lower end pivoted at 29 to the end of arm 26 and extends upwardly through a hole in bracket 21 and terminates above the bracket in a threaded section to which two adjusting nuts 30 are connected, one of which serves as a lock nut. Attached to rod 28, directly below bracket 21, is an arm 31 that can be moved longitudinally on rod 28 and be clamped in adjusted positions by a set screw 32 or any other suitable means. Attached to side 10R is an anchor loop 33 such as an eye bolt, which forms a stationary anchor for the lower end of spring 34 whose upper end is attached to arm 31. Spring 34 is always under tension and therefore tends to move rod 28 downwardly. From Fig. 5 it will be seen that the up and down movement of rod 28 rocks pawl 27 about its pivot. When the ram plate is in its uppermost position, as shown in Fig. 2, pawl 27 is in the full line position which is the position that corresponds to open position of the clutch. When the operator exerts sufficient pressure on pedal bar 19, levers 18 move to the dotted line position shown in Figs. 3 and 5 and closes the clutch, whereupon the cam shaft starts turning and moves the ram plate downwardly. As bracket 21 moves downwardly, spring 34 moves rod 28 downwardly and turns pawl 27 in a counterclockwise direction. When bracket 21 has moved away from nut 30, the pawl is then in the dotted line position shown in Fig. 5 and prevents levers 18 from moving upwardly in response to the force exerted by spring S; the clutch therefore, remains closed until lever 18 is released which occurs when bracket 21 in its upward movement engages nuts 30 and moves bar 28 upwardly to a point where lever 18 is released whereupon spring S immediately moves the parts to the full line position shown in Fig. 5 and opens the clutch. The exact point at which lever 18 is released and the clutch opens is determined by the position of nuts 30 and can therefore be adjusted.

In the event that the automatic clutch release is not wanted, hook 35 which is pivoted at 36 to the upper end of arm 37, is moved into the dotted line position shown in Fig. 5 and holds pawl 27 in inoperative position.

Attention is directed to the fact that presses equipped with the automatic clutch latching and automatic clutch release do not require the operator to exert pressure on the pedal rod continuously during the entire cycle of ram plate

movement as is now necessary. With presses provided with the control means above described, the operator exerts a single pressure on the pedal rod, which moves it into latching position; he can then remove his foot from the pedal bar until he initiates the next cycle.

This attachment is simple and can readily be attached to existing presses. If the control means is built into the machine at the factory, it is obvious that the several elements can be replaced by equivalent elements located differently, but still performing the same function.

What is claimed as new is:

1. The combination with a press brake having its working head cam-engaged with a shaft for reciprocation of a ram plate by rotation of the shaft, a clutch adapted to engage the shaft with driving means, a spring held foot treadle adapted to be depressed in the direction of the working stroke of the ram plate, and clutch shifting means adapted to shift said clutch to the shaft engaging position responsive to the depression of the foot treadle; of a bell crank with one arm forming a hook adapted to latch the foot treadle in its depressed position and the other arm forming a lever movable in the direction of the foot treadle depression to rotate the hook arm into latching position, means to resiliently hold the bell crank in the latching position, a rod connected to the lever arm, a bracket on the ram plate slidably engaging said rod, and a stop on the rod adapted to be engaged by the bracket at the retracted position of the ram plate and to hold the bell crank in the unlatching position at said retracted position.

2. A device in accordance with claim 1 in which means is provided for holding the bell crank in unlatching position independently of the position of the ram plate.
